UNITED STATES PATENT OFFICE.

RICHARD S. BROOKS, OF BONNER SPRINGS, KANSAS.

GATE.

No. 919,122.

Specification of Letters Patent. Patented April 20, 1909.

Application filed November 9, 1907. Serial No. 401,507.

To all whom it may concern:

Be it known that I, RICHARD S. BROOKS, a citizen of the United States, residing at Bonner Springs, in the county of Wyandotte, State of Kansas, have invented certain new and useful Improvements in Gates; and I do hereby declare the following to be a full, clear, and exact description of the invention, such as will enable others skilled in the art 10 to which it appertains to make and use the same.

This invention relates to gates and more particularly to that class which are designed to be opened by the passage of the wheels of a vehicle over a trip and the primary object 15 of the invention is to provide a gate of this class which will be easy to operate and simple in its construction, its simplicity of construction adapting it for use in all climates.

More specifically stated, the gate is of that type which are swung from open to closed position in a vertical plane and which are maintained throughout their movement, in horizontal position, and I have provided 20 means whereby the gate may be opened upon the approach of a vehicle and closed after the vehicle has passed, and also means for slackening the speed of movement of the gate toward either limit of its movement. I have 25 found that one disadvantage apparent in gates of this type lies in the fact that no means is provided for holding the gate against movement in a manner similar to the ordinary swinging gate and with the object in 30 view of providing as far as possible a perfect construction of gate of this class I have conceived the idea of providing means whereby such movement of the gate will be positively prevented so that the stock cannot injure the 35 gate by moving it out of proper alinement.

In connection with my gate I have further provided power transmitting means of such character as to permit of the passage of the rear wheels of a vehicle after one or the other 40 of the trips has been operated by one of the front wheels thereof and have also so constructed the power transmitting mechanism that the gate may be built or set upon the ridge of a hill, in a hollow, or upon uneven 45 ground of any character whatsoever without any loss of the efficiency of the said mechanism.

In the accompanying drawings, Figure 1 is a side elevation of the gate, the same being 50 in closed position, Fig. 2 is a similar view of the opposite side, the gate being in open posi-

tion, Fig. 3 is a top plan view of the gate in closed position, Fig. 4 is an end view thereof in open position, Fig. 5 is a detail vertical sectional view taken to one side of one of the 60 bearings for one of the trips and showing in full lines the relative position of the parts when the gate is closed and in dotted lines their relative position when the gate is open; Fig. 6 is a vertical sectional view through 65 one of the gate posts and the corresponding end of the gate showing the means for preventing lateral movement of the gate, Fig. 7 is a detail view of one of the universal joints for the power transmitting shaft. 70

In the drawings, the gate is shown as working between a pair of spaced parallel upright posts 10 and a post 11, the posts 10 being located to one side of the road-way and the post 11 to the other side thereof. 75 A block 12 is set into the road-bed directly inwardly of the post 11 and a similar block 13 is set into the road-bed inwardly of the two posts 10 and in a plane intermediate the same. Similar blocks 14 are set into the 80 ground to that side of the road to which the gate is to be swung to open position and the function of these four blocks will presently be fully explained.

Journaled in suitable bearings 15 upon the 85 posts 10 is a shaft 16 and rigidly connected to this shaft by means of clips 17, is a pair of bars 18 which extend in spaced parallel relation with respect to each other. A rock shaft 19 is journaled in suitable bearings 20 90 which are fixed upon the sides of the post 10 opposite to the bearings 15 and rigidly connected by means of clips 21 to this rock shaft is a pair of spaced parallel bars 22. The gate proper may be of any desired construction although it is here shown as consisting of end and intermediate uprights 23 and horizontal bars 24. The upper ends of the arms 18 are pivotally connected as at 25 to one of the upper horizontal bars 24 of 100 the gate and to one side of the intermediate upright 23, the arms 22 being connected, also pivotally, at their upper ends to the said bar 24 as indicated at 26 but at the other side of the intermediate upright 23. The 105 points of pivotal connection of the bars 18 and 22 are spaced apart a distance equal to the distance between the shaft 16 and the rock shaft 19 and it will thus be seen that not only are the bars of each pair held in 110 parallel relation, but that the two pairs of bars are at all times held in parallel relation

with respect to each other and it will further be understood that rotation of the shaft 16 will result in a vertical swinging movement of the bars 18 and 22 and a similar movement of the gate proper, the gate being maintained by the manner of connecting the bars 18 and 22 therewith at all times in horizontal position. As the gate is swung, in a manner which will be presently described, from one position to another, it seats, when closed, upon the blocks 12 and 13 at its respective ends and when open upon the blocks 14. In order that the gate may be swung as stated, I have provided suitable trips and a power transmission mechanism connecting the trips and the shaft 16 whereby the shaft may be rotated upon actuation of the trips and this mechanism will now be described. Suitable blocks 27 are set into the road-bed one to each side of the gate and upon each of these blocks is fixed a bearing 28. Journaled in each of these bearings is a shaft 29, this shaft being in alinement with the shaft 16 and fixed upon that end of each shaft 29 which is directed toward the shaft 16 is a sleeve 30 provided with a yoke portion 31, there being a similar sleeve 32, having a yoke 33, fixed upon each end of the shaft 16. The arms of each of these yoke portions are formed in their ends with openings 34 and the arms of the yokes upon the shaft 16 are disposed at right angles to the arms of the yokes upon the shafts 29. A plate 35 is provided with four studs which are engaged at their ends in the openings in the two yokes at each side of the gate and serve to connect the said yokes in a manner substantially like a universal joint it being understood that by this construction the shafts 29 may be disposed at an angle or inclination to the shaft 16 without the efficiency of the device being destroyed.

Fixed upon the outer end of each of the shafts 29 is a bevel gear 36 and meshing with this bevel gear is a similar gear 37 which is loosely carried at the end of a rocking trip 38, it being understood that two of these rocking trips are employed one to each side of the gate. Each of the rocking trips is substantially U-shaped in form and has its connecting portion indicated by the numeral 39 and its spaced portions 40 formed with right angularly extended journals 41 which are engaged in suitable bearings 42 fixed upon blocks 43 set into the road-bed. It is upon one of these journals 41 of each of the rocking trips that the gears 37 are supported and these gears, as stated, are loose upon the trips. However, in order that the rocking 60 of the trips may rotate the gears, the sleeve of each gear is cut away substantially to the extent of a quarter circle as is indicated at 44 and working in this cut away portion is a stud 45 formed upon the said journal of the trip. The operation of these trips will

presently be fully explained. Coiled around the above mentioned journal of each rocking trip is a spring 46 which is connected at one of its ends to the adjacent bearing and has its other end extended upwardly 70 and secured to the adjacent connecting portion of the trip, it being understood that these springs serve to hold the trips normally in vertical or operative position.

From the foregoing description of my invention it will be understood that the gate being closed, depression of either of the trips in a direction toward the gate will serve to swing it to open position, this depression of the trip being caused by one of the front 80 wheels of the vehicle traveling along the road and that after the gate has been so swung, either of the trips may be depressed in a direction toward the gate but without any result being produced. However, after 85 the vehicle has passed the gate, the front wheel of the vehicle will strike the trip at the other side of the gate and depress it in a direction away from the gate. This will result in its being swung to closed position and after the closing trip has been so operated to close the gate by the front wheels of the vehicle, the rear wheels may pass thereover without producing any effect.

In order to permit of ready operation of the gate and to reduce the power necessary to its operation, an expansible spring 47 is connected at its upper end, permanently, to one of the posts 10 adjacent the upper end thereof and at its lower end, to an eye bolt 48 100 which is engaged through the adjacent one of the bars 22 this engagement being had through one of a plurality of openings 49 formed in the said bar, it being understood that by the provision of this plurality of openings, the tension of the spring may be adjusted. The tendency of this spring is to normally raise the gate, this tendency being overcome to a considerable degree by the weight of the gate. It will further be understood that the tendency of this spring to raise the gate will allow the gate to drop slowly and evenly to either extreme of its limits of movement, jar being in this manner obviated.

The means, heretofore mentioned, for the purpose of preventing movement of the gate in a manner ascribed to the ordinary swinging gate, consists of a pair of wooden lugs 50 which are fixed between the outer pair of end 120 uprights 23 and which are designed to seat, when the gate is closed, in recesses 51 formed in the opposing face of the post 11, these recesses being gradually deepened downwardly or in other words having their rear walls inclined or cut at an angle as is indicated by the numeral 52. It is also preferable to broaden these recesses at their upper ends and form them at and adjacent their lower ends, where they are deepest, of a width 125 130

equal to the thickness of the lugs 50. It will be understood from the foregoing that when these lugs are seated in the recesses, the gate will be prevented from moving in the manner 5 of a swinging gate as stated above.

To return to the trips and the gears carried thereby, it might be stated that to more clearly define the structure, the gears carried by the journals of the trips operate only 10 when the trips are moved to bring the studs to bear against the ends of the cut away portions of the gears, the trips having free movement in the other direction.

What is claimed, is—

15 1. A device of the class described comprising a vertically movable gate, a shaft mounted for oscillation to move said gate, trips including each an inverted U-shape portion, gears carried by the shafts and by 20 each of the trips whereby the shafts may be oscillated upon operation of the trips, bearings in which the trips are mounted, a spring engaged around each of the trips, the said spring being connected at one of its ends to 25 the bearings and engaged at its other end

with one of the arms of the inverted U-shaped portion of the trip, the gears upon the trips having a limited rotary movement thereupon, the springs serving to return the trips to raised position after actuation. 30

2. A device of the class described comprising a pair of uprights, parallel shafts journaled upon the uprights, arms secured at their lower ends to the shafts, a gate, the said arms being secured at their upper ends to the 35 gate in parallel relation throughout their extent, means whereby one of said shafts may be rotated, a spring connected to one of the uprights, one of the arms being formed with a plurality of openings, and the spring being 40 provided at its opposite end with an element insertible in said openings interchangeably whereby the tension of said spring may be varied.

In testimony whereof, I affix my signature, in presence of two witnesses. 45
